FUSE FOR A PROJECTILE AND APPLICATIONS THEREOF

Joseph Raymond Jasse, Paris, France, assignor to Societe Nouvelle des Etablissements Brandt, Paris, France, a French body corporate

Application December 20, 1954, Serial No. 476,488

Claims priority, application France December 24, 1953

4. Claims. (Cl. 102—78)

The present invention relates to self-propelled projectiles or rockets and like machines which when launched or fired are subjected to a relatively small acceleration comprised for example between 20 g and 150 g, g being the acceleration of gravity, for a certain lapse of time corresponding to a travel of at least about 50 metres from the launching apparatus.

The invention has more particularly the object to provide a fuse suitable for incorporation in projectiles of the aforementioned type and which is very safe to use and extremely simple.

It has notably the object to provide a fuse of the type having a firing pin and a detonator support which are capable of relative motion, and which comprises in combination with the firing pin and the detonator support: a retractable spacer device which is adapted to be interposed in its operative position between two support surfaces, one of which is provided on the firing pin and the other on the detonator support, for maintaining these elements separated from one another at rest and when launching or firing while the acceleration of the projectile exceeds a minimum safety value, which in the extreme case may be zero, this device being automatically retracted when the acceleration drops below said value; a lock for maintaining the spacer device in operative position and an arming device for automatically retracting said lock when the fuse is subjected to an acceleration which exceeds said minimum value and has such duration that it could not occur during handling or during an accidental fall of the projectile provided with the fuse.

Thus while handling the projectile the arming device cannot be armed and the lock remains in its operative position so that it maintains the spacer device in its proper operative position between the firing pin and the detonator support, thus rendering percussion impossible.

Further, during the launching or firing of the projectile, the acceleration is such that the arming device progressively retracts or withdraws the lock and thereby permits the spacer device to retract itself automatically when the acceleration drops to said minimum value (which corresponds to safe operation in the vicinity of the muzzle of the gun or launching device) and from this moment onward the fuse is armed.

A further object of the invention is to provide a self-propelled projectile or like machine and in particular a self-propelled hollow-charge projectile provided with the above-mentioned improved fuse.

Further features and advantages of the invention will be apparent from the ensuing description.

In the accompanying drawings given merely by way of example:

Fig. 1 is an elevational view with a partial diametral section of a fuse embodying the invention at rest;

Fig. 2 is a cross-sectional view along line 2—2 of Fig. 1;

Fig. 3 is a longitudinal partial sectional view showing

2

the fuse in its armed condition, that is ready to operate upon impact;

Fig. 4 is a side elevational view of a movable sleeve which forms part of the arming device for the rocket;

Fig. 5 is a longitudinal sectional view showing the forward part of a projectile having a hollow charge and provided with the fuse shown in Figs. 1 to 4;

Fig. 6 is a partial sectional view of a first variant of the fuse of the invention shown at rest;

Fig. 7 is a longitudinal sectional view of another variant of the fuse which is more particularly adapted for a projectile having a hollow charge;

Fig. 8 is a similar partial sectional view of a variant of the fuse intended for a projectile whose starting acceleration is low, and

Fig. 9 is a cross-sectional view along line 9—9 of Fig. 8.

According to the embodiment shown in Figs. 1 to 4, the fuse of the invention comprises a cylindro-ovoidal body 1 provided with a screw-threaded portion 2 permitting it to be screw-threadedly engaged with the end of the projectile with which it is to be combined, for example with the head 3 (Fig. 5) of a self-propelled rocket 4 the stabilization of which is either gyroscopic or non-gyroscopic by means of fins.

The body 1 is provided with a throughway aperture along its longitudinal axis XX and screw-threadedly engaged at 6 at the forward end of this body, with respect to the direction of flight of the projectile, is a guide 7 for guiding a percussion device. This device comprises a tubular member 8 which is axially slidable in the guide 7. Fitted in this manner is a head or impact nose 9 screw-threadedly engaged with the forward screw-threaded end 10 of an axial striker or firing pin 11 the rear end of which is in form of a percussion point 12.

The head 9 is forwardly flared in the form of a flange 13 and, between the latter and the front end of the guide 7, a ring 14 of elastic material such as rubber is disposed around the member 8.

Around the firing pin 11 is disposed a return spring 15 which bears against a rear shoulder 16 of the guide 7 and furthermore against an inner flange 17 formed in the member 8. This spring 15 tends to urge the percussion device into the position shown in Fig. 1 so that a flange 18 formed on the firing pin 11 encounters in the direction from the rear to the forward end of the projectile, with respect to the direction of flight, the rear face of the guide member 7.

In alignment with the percussion device and at the rear thereof, is disposed a detonator support 19 of brass or similar material which bears by a rear base 20 on a thin relatively weak washer 21 of aluminium or similar material constituting an inner rear abutment inserted at 22 in a ring 23 screw-threadedly engaged in the rear tapped end of the body 1.

The detonator support 19 has a throughway aperture; this aperture is smooth and cylindrical at 24 at the forward end so as to permit the passage of the stem 11 of the firing pin and is tapped at 25 for the purpose of threadedly engaging a cartridge 26 containing the powder charge 27 of the detonator. The latter also includes, in front of this charge, the primer 28 upon which the point 12 strikes for priming the detonation. A spacer ring 29 permits adjusting the exact position of the primer 28 at rest relative to the point 12.

Between the firing pin and the detonator support 19 is disposed, in a state of rest, a spacer device adapted to maintain a certain distance *a* between the point 12 of the firing pin and the primer 28. This spacer device comprises a number of balls 30 of steel or similar material disposed in the annular space formed around the

point 12 of the firing pin between the rear conical surface 31 of the flange 18 of the firing pin and the front surface 32 of the detonator support 19. The surfaces 31 and 32 are conical and their apices are rearwardly directed.

As will be understood, when the fuse is subjected to an acceleration on account of its displacement with the projectile when the latter is launched or fired, inertia tends to apply the balls 30 on the rear seating or face 32. These balls may be expelled or urged outwardly in two possible ways, depending on whether the projectile provided with the fuse is gyroscopically stabilized (in which case the unit rotates about the longitudinal axis of the projectile and the fuse) or non-gyroscopically stabilized by means of fins. These two cases will be examined in turn.

In the case of a rotating self-propelled projectile, on account of centrifugal force, the balls 30 are urged outwardly, but the action of longitudinal acceleration combined with the presence of the conical face 32 (seating for the balls), tends to maintain these balls in position. The apex angle of the conical face 32 is so selected that this action of centrifugal force becomes preponderant only when the acceleration drops to a minimum value corresponding to safety of operation in the vicinity of the muzzle of the gun or launching device. This value must be so selected that, when it is attained, the projectile has already travelled a distance for example greater than 50 metres from the muzzle, which is sufficient for ensuring that the operators of the launching device are safe from any premature explosion of the projectile.

In the case of a non-rotating self-propelled projectile, the balls 30 are capable of leaving their seating only when the acceleration of the projectile has dropped to zero and the following period of deceleration has commenced at the end of the combustion of the propelling charge. The balls are then subjected to the action of inertia which tends to project them forwardly against the front conical surface 31 which, owing to its shape, throws them outwardly.

At rest, the balls are maintained in their annular housing by a lock which forms in fact a screen around this housing. This locking screen comprises a tube 33 which is slidably mounted on the guide 7 of the percussion device and is disposed around the detonator support 19. It is urged forwardly to the position shown in Fig. 1, where it screens off the housing for the balls, by the action of a spring 34 which bears against the flange 20 of the detonator support 19 and against a flange 35 formed on the tube 33. The latter bears, by way of this flange 35, in the forward direction against a front flange 36 formed on a cylindrical sleeve 37.

This sleeve, which forms the main member of the arming device of the fuse, is slidable in the bore 38 of the body 1 of the fuse, this bore being itself cylindrical. It comprises on its outer face two diametrically opposed grooves 39 having a zig-zag shape. The longitudinal sides of each of these grooves comprises a series of semi-circular notches, the latter being staggered from one side of the groove to the other. In each of these grooves 39 extends a locking pin or finger 40 carried by the body 1 of the fuse (Fig. 1).

At the rear, the sleeve 37 includes along its entire periphery a notch forming a shoulder 41 which faces forwardly and is adapted to co-operate with the yieldable or resilient retaining elements formed by strips or blades formed up from a cup 43 which bears against the front face of the rear ring 23. These blades are inclined towards the axis of the projectile so as to hook onto the sleeve 37 when the latter, under the action of inertia, is brought into the rear position shown in Fig. 3.

The weights of the sleeve 37 and the tube 33 and the strength of the spring 34 are such that the sleeve 37 can assume the position shown in Fig. 3 (displacing the

screen 33 and compressing the spring 34) only when the fuse is subjected to an acceleration of finite value and of such duration that it is impossible to obtain in the course the worst conditions of handling, for example when the projectile receives a blow or accidentally falls. The inertia of these elements due to a blow at the highest velocity encountered in accidentally falling is insufficient to obtain a position permitting the tube 33 to unscreen the housing of the balls 30.

At rest, before firing or launching the projectile, the fuse is in the position shown in Fig. 1, the balls 30 disposed between the surfaces 31 and 32 holding the point 12 of the firing pin away from the primer 28. These balls are held in their housing by the locking screen 33 which is itself held in its forward position or operative position by the spring 34. The latter also holds the sleeve 37 or the arming device in its forward position. Each pin 40 is disposed for example in the position shown in Fig. 1 and Fig. 4 at the rear of the corresponding groove 39.

When the projectile is fired, the resultant relatively high longitudinal acceleration (30 g to 150 g for example) causes the sleeve 37 to move rearwardly owing to its inertia, at such velocity that the grooves 39 are capable of passing by the pins 40 without jarring and without rebounding onto the latter. If the position of departure is that shown in Fig. 4, the sleeve 37 is moved in the direction of arrow f^1 relative to the fixed pin 40 and enters into the contact with the latter at the point m and thereafter the sleeve continues to move rearwardly while rotating about its own axis in the direction of arrow f^2 so that the portion mn of the groove slides over the pin 40. Then the latter reaches at 40^a the apex n and the rearward movement of the sleeve continues accompanied by a rotation in the direction opposite to that of arrow f^2 , the sleeve sliding over the pin 40 along the portion op of the opposite side of the groove.

The rearward movement of the sleeve 37 thus continues up to the position shown in Fig. 3 accompanied by the movement of rotation of this sleeve about its longitudinal axis permitting the successive apices of the groove 39 to pass by the pins 40. When the sleeve 37 attains the position shown in Fig. 3, it engages the blades 42.

In the course of its displacement the sleeve 37 draws back the screen 33 which frees the balls 30. As has been explained above, these balls 30 are urged against their rear seating 32 by the action of the acceleration of the projectile. When this acceleration falls to the aforementioned safety value the balls 30 are thrown outwardly, as explained above, either by the action of centrifugal force if the projectile rotates or by the action of inertia if the projectile does not rotate and these balls become lodged in the forward end of the bore 38 of the body 1 of the fuse. Thenceforth the fuse is armed and nothing opposes the percussion device from approaching the detonator support 19.

The percussion device and the detonator support are brought together when the percussion device is urged rearwardly relative to the projectile if the latter attains the target by its nose or head 9, this head compressing the rubber ring 14 and thus causing the firing pin 11 to move rearwardly. Furthermore, the percussion device and the detonator support are urged together in any case, even if the projectile does not attain the target by its head 9, under the action of inertia which projects the detonator support 19 forwardly so that finally the distance a is traversed and the point 12 of the firing pin strikes the primer 28 and thus fires the detonator which in turn ignites the explosive charge of the projectile.

The behaviour of the projectile from the point of view of safety under various circumstances before firing or launching will now be examined.

(a) *Security in the event of the projectile falling*
If a rocket equipped with the fuse is dropped from

an aircraft without having ignited the propelling charge of this rocket, the fuse falls on to its nose in the unarmed state. The maximum velocity of the drop is not sufficient, as mentioned above, to enable the sleeve 37 to move sufficiently rearwardly, in opposition to the action of the spring 34, to allow the tube 33 to unscreen the annular housing containing the balls 30. The fuse therefore encounters the ground unarmed and the impact is transmitted from the firing pin to the detonator support 19 through the balls 30. But there is no possibility of these balls becoming buried in the detonator support, even if the latter is of a relatively weak material such as brass, because the thrust communicated by the balls to the detonator support causes the rupture of the rear abutment constituted by the annular washer 21 which is made weak expressly for this purpose. Thus the unit comprising the percussion device and the detonator support recoils with respect to the projectile and the point of the firing pin is unable to strike the primer 28.

(b) *Security in respect of arming the fuse*

In the event of a blow on the rear end of the projectile in which the fuse is incorporated, the resultant sudden acceleration of short duration causes the sleeve 37 to travel rearwardly to a limited extent under the effect of inertia so that the side of the first notch of each groove 39 situated above each pin 40 (Fig. 4) suddenly abuts against the latter at point *m*. Owing to the resilience of the material, the sleeve springs back and returns to its initial position.

It will be noted that this does not occur under the effect of acceleration due to actually firing or launching the projectile for this latter acceleration is of a limited value which does not result in the sleeve 37 springing back on the pins 40; this acceleration is, however, such that due to the force of inertia the sleeve 37 is capable of compressing the spring 34. Furthermore, this acceleration has sufficient duration to ensure that the sleeve 37 engages the locks 42 in the manner described above. Such conditions cannot of course occur in the course of handling the fuse or the projectile equipped with this fuse.

(c) *Security during the first part of the trajectory*

This has been dealt with in the description of the normal firing of the projectile. It is recalled that the acceleration at the departure of the projectile causes the balls 30 to press against the seating 32, these balls remaining there for a period of time sufficient for the actual arming of the fuse to occur when the balls 30 are thrown off their seating subsequent to the withdrawal of the tube 33. This occurs only when the projectile is outside the range of the operators of the launching device.

Reference will now be had to Fig. 5, which shows the fuse F of the foregoing example in position on the front part of a self-propelled rocket having a hollow charge. This hollow charge 43 terminates at the forward end in a conical recess 44 and thus forms at 44^a the usual hollow charge cavity. This cavity is of course of sufficient size to permit an unhindered rearward displacement of the detonator support 19 in the event of a blow being received before the fuse is armed.

It will be noticed that the rear of the fuse is surrounded by a sealing sleeve 45.

The hollow charge comprises at the end of a bore 46 extending the funnel 44 a secondary detonator 47 which is adapted to be ignited by the fuse detonator F.

A variant of the fuse has been shown in Fig. 6 this variant being adapted to operate simply under the effect of inertia, the firing pin being fixed. This firing pin 11^a including its point 12 is integral with the portion 7^a which is directly threadedly engaged at 6 in the body 1 of the fuse. Thus there is no rubber ring such as that shown at 14 in respect of the first example. The percussion is obtained simply under the action of inertia which

causes the detonator support 19 to move forwardly under the effect of the impact. The portion 7^a of the firing pin support is preferably hollowed out at 7^b so that this element is less massive and is capable of being more easily destroyed in the same way as the rest of the fuse when the detonator explodes, whereby no obstacle is in the way of the forward-shooting explosive force produced by the hollow charge; this is more important if the hollow charge is small.

Fig. 7 shows a variant of the fuse in position on a rocket not having a hollow charge. The front portion of the ogive is seen at 48, this being filled around the fuse with the powder charge 49.

The front part of the fuse is identical to that of the first example and it differs therefrom only in that the rear support ring 23 is replaced by a long member 23^a at the rear end of which is threadedly engaged the auxiliary detonator 50. The element 23^a constitutes an extension which allows the free rearward movement or recoil, after rupture of the rear abutment ring 21^a, of the unit comprising the percussion device and the detonator support 19 in the event of a blow being received before arming. Extension 23^a should be long enough to avoid that the detonator support should rebound from the rear of said extension, which could bring the detonator back against the firing pin. As a result of said length, during normal percussions of the projectile, the flames from detonator 26—27 may not be sufficient to fire the useful charge, and auxiliary detonator 50 serves as a useful and necessary relay to avoid misfiring.

The fuse and its extension 23^a and the auxiliary detonator 50 are housed in a sealing tube 51.

The various above-described examples relate to fuses for rockets having a relatively high acceleration upon launching or firing, this acceleration being capable of attaining about 150 g as in the case, for example, of fighter rockets fired from an aircraft against an enemy aircraft.

Figs. 8 and 9 relate to a variant of the fuse which is more particularly suitable for a ground attack rocket intended exclusively for fighting tanks. In this type of rocket the launching acceleration is low and is of the order of 30 g, since the required velocity is less. As the maximum acceleration of the fuse is reduced, it is obvious that that arming device must operate for a lower acceleration, for example 15 g. With such an acceleration for operation of the arming device, handling the fuse is relatively precarious. However, this is remedied by the following two improvements:

(a) The travel of the arming device is considerably increased (compare Figs. 7 and 8), which renders an acceleration of longer duration necessary for causing the sleeve 37^b to engage under the locking blades 42.

(b) A safety pin is provided which is adapted to immobilize this sleeve 37^b until required. This pin comprises the end 52 of a spring 53 whose shape in plan is shown in Fig. 9. This spring 53 is engaged in an outer groove 54 of the ogive 55 of the fuse and the end 52 of the spring extends radially through said ogive and enters an aperture 56 formed in the sleeve 37^b.

Before launching or firing the projectile, the pin 52 is of course withdrawn. From this moment the fuse behaves in the same way as the fuses of the preceding examples except that the detonator support 19^b bears directly on the body 57 of the projectile on an inner unbreakable flange forming rear abutment. In this case the unit comprising the detonator support and the percussion device separated by the balls 30 is incapable of displacement, since there is no rear abutment capable of rupturing, such as the washer 21 of the preceding examples (Fig. 1). The rupture of this washer is replaced in the present example, shown in Fig. 8, by a rupture of the rear part of the detonator support 19^b. The wall of this part is made very thin from *r* to *s* so that when a blow is received prior to arming, the thrust

exerted by the firing pin on the detonator support through the medium of the balls causes this rear part to break.

If need be, the fuse of the invention may be so adapted as to permit its operation before the end of the combustion of the propelling charge of the projectile, when this fuse strikes a hard obstacle such as armour plating. This may be obtained by so selecting the hardness of at least one of the seatings for the balls 30 that beyond a certain velocity of the projectile, upon contact with the obstacle, these balls embed themselves in this seating to such depth that the firing pin ignites the detonator. This velocity must of course be greater than the maximum velocity developed when the projectile accidentally falls so as to ensure that it is safe to handle. Thus it is necessary to select the detonating mass in such manner as to obtain a force of inertia which is capable of causing the balls to embed themselves sufficiently in their seating. This may be accomplished even if a fragile rear abutment such as the washer 21 shown in Fig. 1 or a breakable column such as the portion *rs* of the detonator support 19^b shown in Fig. 8 is used. The detonator support might for example be made of brass composed of 60% copper and 40% zinc.

It will be observed that in all the examples the detonator of the fuse is housed inside the latter so that its operation destroys the major part of the fuse. This is advantageous in the case of a hollow charge, since no obstacle is left in the way of the gas jet issuing from the hollow charge, this jet being therefore fully effective.

Although specific embodiments of the invention have been described hereinbefore it is to be understood that many changes and modifications may be made therein without departing from the spirit of the invention or the scope of the appended claims.

Having now described my invention what I claim as new and desire to secure by Letters Patent is:

1. A fuse for a self-propelled projectile, subjected when it is launched to a departure acceleration, comprising in combination: a hollow fuse body, and disposed in said body: an inner rear abutment secured to said body, a detonator support bearing against said abutment, a detonator held on the forward end of said detonator support; a spacer device bearing rearwardly against said detonator support and automatically retractable when said acceleration drops to a minimum safety value, which in the extreme case may be zero, whereby said fuse becomes automatically armed upon the retraction of said spacer device; a firing pin bearing rearwardly directly against said spacer device; said spacer device, in its non-retracted position, maintaining said firing pin separated from said detonator, and upon retraction, re-

leasing said firing pin and allowing the latter to move and to travel rearwardly towards said detonator held by said detonator support in a forward position for fuse firing; said firing pin protruding from the forward end of said body; one of the elements constituted by said rear abutment and said detonator support being breakable; said detonator support moving rearwardly from its forward fuse-firing position upon breakage of said element; in the event of an accidental blow on said firing pin in the unarmed condition of said fuse, and sufficient to induce a rearward travel of said pin towards said detonator support and said detonator, said breakable element being ruptured by said blow, whereupon said detonator support and said detonator travel rearwardly from said forward position before said spacer device, as a result of said blow, becomes embedded in said firing pin or in said detonator support to an extent sufficient to allow the firing pin to encounter said detonator; said rupture of said breakable element and the resultant rearward travel of said detonator support and of said detonator preventing an undesirable and untimely firing of said fuse.

2. A fuse as claimed in claim 1, in which said detonator support is a rigid structure and said rear abutment is breakable.

3. A fuse as claimed in claim 2, further comprising at the rear of said fuse body, a hollow extension for receiving said detonator support and said detonator when they move rearwardly after breakage of said rear abutment, said extension extending substantially entirely rearwardly of said rear abutment; and a second detonator attached to the rear end of said extension, and relaying the flames from the detonator held on the forward end of said detonator support to the useful charge of said projectile upon normal percussions of said projectile.

4. A fuse as claimed in claim 1, in which said rear abutment is a rigid structure, and said detonator support comprises, rearward of its detonator-carrying forward end, a thin wall capable of breaking when said firing pin receives said accidental blow.
